UNITED STATES PATENT OFFICE.

HENRY C. MOORE, OF TAMA CITY, IOWA.

DIRECT-DRAFT ROAD AND DITCHING MACHINE.

SPECIFICATION forming part of Letters Patent No. 365,845, dated July 5, 1887.

Application filed March 12, 1887. Serial No. 230,633. (No model.)

To all whom it may concern:

Be it known that I, HENRY C. MOORE, a citizen of the United States, residing at Tama City, in the county of Tama and State of Iowa, have invented certain new and useful Improvements in a Direct-Draft Road and Ditching Machine; and I do hereby declare the following to be a full, clear, and exact description of the invention, such as will enable others skilled in the art to which it appertains to make and use the same.

My invention relates to certain improvements in the construction and combination of parts of the direct-draft road and ditching machine provided with a reversible scraper, for which I filed application for Letters Patent July 6, 1886, Serial No. 207,251.

One object of my invention is to provide improved means for governing the movement and position of the draft beams and chain of a scraper in adjusting and reversing the same.

A further object of my invention is to provide improved means for the convenient connection and disconnection of the beams to and from a stationary draft-iron, said means being simple and effective in their construction and operation.

I attain these objects by the mechanism illustrated in the accompanying drawings, where- 30 in the same letters of reference indicate the same parts, and in which—

Figure 1 is a detail perspective view of a reversible scraper and its connections, with part of my improvements shown in connection therewith. Fig. 2 is a top plan view of a portion of the connections of a reversible scraper, showing my improvements in full in connection therewith. Fig. 3 is a side elevation of a portion of the same, the axle-tree being in section; and Fig. 4 is an end view of a cross-piece of the main frame above, with the dis- connecting-lever mounted thereon.

A indicates a reversible or adjustable scraper, and B a portion of the front axle, of a direct-draft road or ditching machine. The scraper A is secured to draft-beams b b, and to the forward ends of said beams the draft-chain b' is attached. This chain passes around the shaft or king-bolt d, which may be provided with an anti-friction roller for the engagement of said chain, if found necessary or desirable. The king-bolt d passes through the

rear loop of the draft-iron a', which is also constructed with a loop projecting forward of the axle-tree B for attachment to the whiffle-tree or other draft devices of the running-gear. This draft-iron a' is also provided with rearwardly-projecting shanks a³ a³, which spread outwardly from each other and turn up at their rear ends in the form of shanks a⁵ a⁵. Said shanks rest in sheaths a⁴ a⁴, formed integral with the guides or sleeves a a, through which the draft-beams b b and chain b' are moved. These guides or sleeves a a are constructed of plates of metal of sufficient strength to resist the weight falling upon them, and they are in the form of what may be termed "irregularly-shaped channels" provided with sides of considerable height and converging somewhat toward their front ends, with wide centrally-grooved bottoms, and with wide open mouths at their rear ends, having drooping lips. These guides or sleeves, as stated, are formed integrally with the sheaths a⁴ a⁴, which surround the shanks a³ a³ of the draft-iron a'; or they may be provided with short cross bars or straps for bracing and retaining said shanks in position, whereby a sure connection between said sleeves and the draft-iron is maintained.

A bar, c, is placed across and loosely upon the sheaths a⁴ a⁴ of the guides or sleeves a a, and is arranged between the turned-up ends a⁵ a⁵ of the draft-iron, shanks a³ a³, and the front ends of the said guides or sleeves, and beneath one of the beams b b and the chain b'. To the ends of this bar c chains c' c' are attached, which are united by a ring, c², to which is secured by suitable connections a treadle-lever mounted on the frame above. The chains c' c', as shown, are attached to the ends of the bar c outside of one of the draft-beams b b and of the chain b', and thereby prevent said bar from working horizontally out of place.

To the rear side of the axle-tree B is secured an eye, e, as shown in Figs. 2 and 3, through which one end of a chain, e', attached to the bottom of the bar c, passes and connects with a spiral spring, e², secured at the center of the cross-bar. This bar e² rests upon and is connected to the sheaths which inclose the shanks of the draft-iron a' by suitable staples.

In reversing the scraper the eye on the front end of one of the draft-beams b b is drawn by the chain b', which connects the two beams,

into the mouth of one of the guides or sleeves *a a*. Then, as the channel of the said guide or sleeve narrows toward its front end, the eye of said beam rises over the lip and sloping sides 5 thereof until said eye passes to the rear of the sides of said guide or sleeve. This brings the eye directly over one of the turned-up ends *a⁵* of the shanks of the draft-iron *a*, upon which it drops by gravity and steadily holds the 10 scraper at the desired angle of adjustment.

When it is desired to disconnect either of the draft-beams *b b* from the turned-up ends *a⁵ a⁵* of the shanks of the draft-iron *a'*, the bar *c* is raised by a treadle-lever, *c³*, mounted upon the 15 main frame of the machine, and with it is also raised the beam and chain, thus releasing said beam from said upturned ends *a⁵ a⁵* of said draft-iron. This raising of the parts named causes a downward draft upon the chain *e'*, 20 which is attached at one end to the bar *c* and at the other end to the spring *e³*, secured to the bar *e²*. It is obvious that as said chain *e'* passes through the fixed loop *e* on the axle the spring *e³*, which connects said chain and the bar *e²*, 25 will gently draw said bar downward as the bar *c* is raised, and that the shanks *a³ a³* of the draft-iron will be correspondingly depressed by said bar *e²* resting thereon. The depression of the draft-iron and its shanks is permitted, thus effecting ready disconnection of 30 the draft-beams, and with little frictional resistance. When the treadle-lever *c³* above is released, the parts resume their normal positions, as will be readily understood.

35 Having thus described my invention, what I claim as new is—

1. In a direct-draft road or ditching machine, the combination of the draft-iron, the draft-beams, the chain, the adjustable scraper

or plow, and conducting guides or sleeves 40 which act as keepers for said beams and chain during the adjustment of the scraper, substantially as described.

2. In a direct-draft road or ditching machine, the combination of an adjustable 45 scraper, and means for adjusting and operating the same, with the disconnecting-bar, substantially as described.

3. The combination, with the adjustable 50 scraper, the draft-iron having shanks provided with upturned ends, and the draft beams and chain connecting said parts, of the conducting sleeves, and the bar for disconnecting the said beams and chain from the draft-iron, substantially as described.

4. The combination, with the adjustable 55 scraper A, the conducting-sleeves *a a*, the draft-beams *b b*, the chain *b'*, and the front draft-iron, *a'*, of the disconnecting-bar *c*, the chains *c' c'*, chain *e'*, the eye *e*, the spiral spring *e³*, and the bar *e²*, substantially as described.

5. In a direct-draft road and ditching machine, the combination of a reversible scraper, the draft-beams having eyes in their front ends, the draft-chain, and the draft-iron provided 60 with shanks having upturned ends, and the conducting sleeves or guides formed as described, whereby when said scraper is brought into proper reversed position an automatic connection of the eyes of the beams with the 65 upturned ends of the shanks of said draft-iron is effected, substantially as described.

In testimony whereof I affix my signature in presence of two witnesses.

HENRY C. MOORE.
